CONTAINER FOR A PHOTOGRAPHIC CAMERA OR SIMILAR ARTICLE

John A. Beaumont, Walpole, Mass., assignor to
Polaroid Corporation

Continuation-in-part of design application Ser. No.
268,153, June 30, 1972. This application Feb. 28,
1974, Ser. No. 446,589

Term of patent 14 years

Int. Cl. D9—03

U.S. Cl. D9—232

FIG. 2

FIG. 3

FIG. 4

FIG. 6

FIG. 5

FIG. 1 is a top perspective view of a container for a photographic camera or similar article showing my new design in an open position;

FIG. 2 is a bottom plan view thereof;

FIG. 3 is a top plan view in a closed position;

FIG. 4 is a side elevational view thereof;

FIG. 5 is an end elevational view thereof;

FIG. 6 is a bottom plan view thereof; and

FIG. 7 is a fragmentary sectional view taken on the line 7—7 of FIG. 1.

This is a continuation-in-part of design application Ser. No. 268,153, filed June 30, 1972.

I claim:

The ornamental design for a container for a photographic camera or similar article, substantially as shown and described.
